INVENTOR

UNITED STATES PATENT OFFICE.

GEORGE M. HOLLEY, OF DETROIT, MICHIGAN.

EXHAUST-HEATED OIL-VAPORIZER.

1,400,287.

Specification of Letters Patent. Patented Dec. 13, 1921.

Application filed December 13, 1920. Serial No. 430,365.

To all whom it may concern:

Be it known that I, GEORGE MALVIN HOLLEY, a citizen of the United States, residing at Detroit, in the county of Wayne and State 5 of Michigan, have invented certain new and useful Improvements in Exhaust-Heated Oil-Vaporizers, of which the following is a specification.

This invention relates to externally heated 10 oil fuel vaporizers. The vaporizer is intended to be used in conjunction with an internal combustion engine and to be heated by the exhaust gases therefrom. A heated rich mixture is produced in the heater, which 15 is subsequently diluted with cold air in a well-known manner.

The object of this invention is to provide 20 an improved form of vaporizer for use with fuels composed of hydro carbons having a wide range of boiling points. Specifically, 25 this invention provides means for removing the various hydro carbons as they each in their turn become vaporized, and thus the unvaporized fuel is progressively heated without super-heating the vaporized fuel. 30 Another object is to provide means whereby any carbon that may accumulate within the vaporizer may be quickly and easily removed. A further object is to reduce the cost of manufacture to a minimum.

Figure I shows the fuel float chamber arranged to furnish the requisite rich mixture to the improved vaporizer, which is shown integral within an exhaust manifold, 35 which manifold also supports the float chamber.

Fig. II shows a transverse section on the line 2—2 of Fig. I through the center of the vaporizer and also shows the details of 40 construction of the vaporizer itself. The means for diluting the heated rich mixture is not shown, as it may be any of the well-known forms and is no part of this invention.

Fig. III shows a section through the passage F taken in the plane 3—3, and one of the horizontal chambers C.

Description.

In Fig. I "A" is the float chamber maintaining the fuel at a constant level and supplying fuel with the air required for

atomizing to the vaporizer "C," which is in the form of a labyrinth or maze. The vaporizer "C" is shown cast integral with 55 in the exhaust pipe or manifold "E," but may be made of a stamping, die casting or of a separate casting. In "C" a cover "F" is provided for inclosing the vaporizer "C" so as to force the vapor to pass back and 60 forth through the channels in "C" as shown by the arrows on Fig. I. In "F" are provided a number of outlets "D," which are arranged adjacent to the under side of the partitions in "C" so as to separate the 65 vapor from the unvaporized fuel. These outlets "D" are preferably inclined in the direction of the flow, as shown in detail attached to Fig. II, so as to still further assist in separating the vaporized from the un- 70 vaporized fuel. From "F" pipe "G" leads the fuel to the diluting means not shown. "B" is the inlet from "A" into "C."

The lowest opening "D" is enlarged so that should the upper opening become 75 clogged with carbon, the engine will still continue to operate, although not so satisfactorily.

Operation.

The rich mixture supplied by "A" is heated in the tube "B" within the exhaust manifold "E." The rich mixture then flows downward through the labyrinth "C," the vaporized fuel and air passing through 85 the outlets D into the cover "F" and so into the pipe "G." By this means the semi-vaporized fuel in the passages which form the labyrinth in "C" is separated, the vaporized fuel passing out of "D" and the unvaporized 90 fuel passing on downward through the labyrinth. Thus, ultimately all of the fuel is vaporized and none of the fuel is super-heated.

Claims:

1. A vaporizer for liquid fuel consisting of a heating pipe adjacent to and surrounding a labyrinth through which the liquid fuel passes and a plurality of outlets from 100 said labyrinth graduated and arranged so as to remove the fuel as it is vaporized.
2. A vaporizer for liquid fuel, consisting of a chamber within a pipe through which a

heating medium passes, a labyrinth within the chamber, a plurality of outlets from said labyrinth, a cover for said chamber containing a common passage for the outlets from the labyrinth.

3. A vaporizer for liquid fuel, consisting of a chamber within a pipe through which a

heating medium passes, baffles within the chamber dividing the chamber into horizontal passages, a cover for the chamber, an outlet for each passage communicating with a common outlet passage in the cover. 10

In testimony whereof I affix my signature.

GEORGE M. HOLLEY.
